UNITED STATES PATENT OFFICE.

ENGELBERT BERGS, OF LUDWIGSHAFEN-ON-THE-RHINE, GERMANY, ASSIGNOR TO BÄDISCHE ANILIN & SODA FABRIK, OF LUDWIGSHAFEN-ON-THE-RHINE, GERMANY, A CORPORATION.

PROCESS OF PRODUCING BORNEOL ESTERS.

No. 903,047.

Specification of Letters Patent.

Patented Nov. 3, 1908.

Application filed October 23, 1906. Serial No. 340,206. (Specimens.)

To all whom it may concern:

Be it known that I, ENGELBERT BERGS, doctor of philosophy and chemist, subject of the King of Prussia, residing at Ludwigshafen-on-the-Rhine, Germany, have invented new and useful Improvements in the Production of Borneol Esters, of which the following is a specification.

My invention relates to the production from pinene hydrochlorid of borneol esters including under this name both the borneol esters proper and the isomeric bodies termed isoborneol esters.

It is stated in the *Annalen* 239, page 6, and in the *Berichte* 32, p. 2308, that by treating pinene hydrochlorid with sodium acetate, or potassium acetate, at a high temperature, for instance at from 180° to 200° centigrade, camphene can be obtained mixed with small quantities of bornyl acetate, or isobornyl acetate. It is further stated in the *Berichte* 32, p. 2309, that by allowing silver acetate to act on pinene hydrochlorid for several weeks at a low temperature, a mixture is obtained which consists chiefly of camphene, but also contains small quantities of isobornyl acetate. It is further stated in the specification of the French patent No. 349,896 that by acting on pinene hydrochlorid with lead acetate for from twenty, to thirty, hours, either at the temperature of boiling glacial acetic acid, or in an autoclave at a temperature of from 130° to 135° centigrade, camphene is obtained, whereas, when these two compounds are allowed to act upon one another in the presence of glacial acetic acid in an autoclave at a temperature of 180° centigrade, bornyl acetate and isobornyl acetate are the chief products obtained. This last method of obtaining the esters is not, however, suitable for being carried out on a commercial scale because of the difficulty of working in an autoclave with glacial acetic acid at such a high temperature.

I have now discovered that by acting on pinene hydrochlorid with a zinc salt of an organic acid, such as zinc acetate, the reaction proceeds differently, in that by boiling these two compounds together in a reflux apparatus in the presence of a medium such as glacial acetic acid, after a short time a product is obtained which is free from

chlorin and from which borneol acetate, if zinc acetate has been used, can be distilled, some of the product being bornyl acetate and some isobornyl acetate. Instead of zinc acetate, the zinc salts of other organic acids, for instance, zinc formate and zinc benzoate can be employed, and other media can be employed in place of glacial acetic acid, for instance formic acid, or diluted acetic acid (containing for example eighty per cent. of acetic acid). When diluted acid is employed, the time required to complete the reaction is longer than when pure acid is used. The reaction which takes place can be represented by the equation

Both the isomeric esters possess the formula $C_{10}H_{17}OCOCH_3$, and the difference of constitution between them is not known. The proportion of isomeric esters to one another in the product appears to vary according to the method in which the reaction is carried out, but it is a matter of indifference in what proportions they occur, for in both forms the borneol ester is equally useful for practical purposes, namely, for the manufacture of camphor.

The following example will serve to illustrate further the nature of my invention and a way in which it can be carried into practical effect, but my invention is not confined to this example. The parts are by weight. Boil together, for about forty-five (45) minutes, in a reflux apparatus, one hundred (100) parts of solid pinene hydrochlorid, fifty-four (54) parts of zinc acetate and one hundred and fifty (150) parts of glacial acetic acid. Allow the mixture to cool slowly and to stand for some time, then distil off the acetic acid *in vacuo* and wash the residue with water, and then distil. The mixture of the esters distils over at a pressure of about twelve (12) millimeters of mercury, at a temperature of from one hundred and two (102), to one hundred and five (105), degrees centigrade, and the said esters can easily be saponified and the corresponding alcohols be produced.

Now what I claim is:

1. The production of borneol esters by

heating pinene hydrochlorid with a zinc salt of an organic acid in the presence of an organic acid substantially as hereinbefore described.

2. The production of borneol esters by
5 heating pinene hydrochlorid with zinc acetate in the presence of acetic acid.

In testimony whereof I have hereunto set

my hand in the presence of two subscribing witnesses.

ENGELBERT BERGS.
